Filed Apr. 14, 1969, Ser. No. 16,729

Term of patent 14 years

Int. Cl. D15—10

U.S. Cl. D80—11

FIG. 1

FIG. 2

FIG. 3

FIG. 4

FIG. 5

FIG. 1 is a perspective view of a refrigerated display case showing our new design;

FIG. 2 is a view top plan thereof;

FIG. 3 is a view in side elevation thereof of the side opposite that shown in FIG. 1;

FIG. 4 is a view in end elevation as seen from the right side of FIG. 3; and

FIG. 5 is a view in end elevation as seen from left side of FIG. 3.

The characteristic feature of our design resides in the provision of an upper peripheral rim about the display portion which extends over the top of the compressor housing, the latter being an extension of the lower portion of the display case.

We claim:

The ornamental design for a refrigerated display case, substantially as shown and described.
